TO RADIO CORPORATION OF AMERICA, OF NEW YORK, N. Y., A CORPORATION OF
DELAWARE

DUPLEX HORN FOR SOUND REPRODUCERS

Application filed February 27, 1922, Serial No. 539,366. Renewed February 21, 1925.

My invention relates to sound reproducers thereby avoiding any distortion of the tonal effects. adapted for reproducing sounds from two different sources, such as those emanating from the reproducer of an ordinary phonograph and those reproduced by a wireless receiving set. Where both phonograph records and a wireless receiving set are available, the reproduction of sound from the two sources is not ordinarily desired at one and the same time. Consequently, a single amplifying horn should be adequate for use with the sound reproducers associated with both of the said sources of sound. However, if reproducers are attached to one and the same horn, the unused inlet connection affords a chamber which tends to reflect the tones from the reproducer which is in use and which undesirably modifies the sounds before they are emitted from the amplifying horn. In one aspect, my invention aims to overcome this difficulty by providing an effective arrangement whereby either of two tone reproducers associated with a single amplifying horn can effectively be connected to the horn while operatively disconnecting the other reproducer, and aims to effect this selective connection of the amplifying horn to either sound reproducer without any modification of the sound emission from the reproducer which is being used.

Furthermore, my invention aims to provide simple means whereby this selective connecting of the amplifying horn to one reproducer and the corresponding disconnection from the other reproducer can automatically be effected in response to the operation of the apparatus associated with one reproducer. Where the record table of the phonograph is propelled by an electric motor, my invention also aims to provide simple means for automatically causing the supplying of current to the motor to change the horn connection from the reproducer of the wireless receiving set to the tone arm of the phonograph. Furthermore, I aim to provide sound passages connected with the inlet end of the amplifying horn and so formed as to present continuously flaring passages from either reproducer to the mouth of the horn,

More particularly, I aim to provide an amplifying arrangement suitable for use interchangeably with a radiophone and a phonograph, and aim to provide simple means whereby a single amplifying horn will normally be connected to the sound reproducer of the radiophone, whereby the connection will automatically be switched to the tone arm of the phonograph when the motor of the phonograph is started, and whereby the connection will be switched back to the radiophone when the phonograph motor is stopped. Still further and also more detailed objects will appear from the following specifications and from the accompanying drawings, in which

Fig. 1 is a fragmentary vertical section through the cabinet of an electrically driven phonograph equipped with my invention, with the amplifying horn and the inlet connections thereto shown in longitudinal section.

Fig. 2 is a similar section through the portion of the cabinet below the record turn table, showing the amplifying horn and the inlets thereto in elevation and showing one form of magnetic means for automatically shifting the horn inlet connection from the radiophone reproducer to the tone arm of the phonograph.

Fig. 3 is a phantom view of the amplifying horn and of the inlet connections to the same, showing desirable cross sections for these parts and also showing the valve or flap which selectively controls the inlet connections.

In the embodiment of the drawings, I am showing a phonograph cabinet 1 having mounted therein a phonograph including a record table 2 adapted to be rotated by an electric motor 3. The reproducer 4 of the phonograph is connected by the usual tone arm 5 to a neck 6 leading first downwardly and then through a bend into the smaller or inlet end of an amplifying horn 7. Adjacent to the juncture of the neck 6 with the inlet end of the horn and desirably arranged symmetrical to the said neck is an auxiliary

inlet 8 leading to a radiophone reproducer 9 which is connected by wires 10 to a radiophone receiving system. The two inlets 6 and 8 are desirably connected to the neck end 5 of the amplifying form in substantially a Y formation and adjacent to the juncture of the arms of the Y at the back of the interior of the said connecting chambers I pivot a flap or valve 11. This flap is desirably mounted 10 on a rock-shaft 12 extending beyond the exterior of the tubular members forming the said inlet connections and is connected to suitable means for rocking the shaft so as to present the flap or valve in either of the two operative positions in which it selectively connects one or the other of the inlets to the amplifying horn. For this purpose, I am here showing the rock shaft 12 as having fastened to it an arm 13 carrying the curved 15 core 14 of a solenoid whose winding 15 is connected in series with one of the wires 16 through which current is supplied to the motor 3. Moreover, the solenoid core and the arm 13 are so disposed, as for example after 20 the manner shown in Fig. 2, that gravity will normally swing them in a clockwise direction, thereby swinging the flap 11 to the position shown in full lines in Fig. 1 or that in which this flap closes the connection from the 25 tone arm of the phonograph to the amplifying horn 7 and opens the corresponding connection to the radiophone reproducer 9. Consequently, the operator of such a duplex sound reproducing appliance can operate his 30 radiophone at any time and can have the resulting tones or other sounds amplified by the horn 7 without paying any attention to the position of the flap or valve 11 or to any other of the parts above described. Likewise, if he wishes to use the phonograph, he 35 merely switches on the current for the operating motor in the usual manner, in doing which he causes the current to energize the coil 15 so that the pull of this on the coil 14 40 will swing the rock-shaft to the position shown in dotted lines in Fig. 1. In other words, gravity normally maintains the connection to the wireless receiving set, starting the phonograph automatically shifts the connection to the latter, and gravity restores 45 the connection to the radiophone whenever the phonograph motor is stopped.

To avoid a muffling of sounds within the 50 passages leading to the main portion of the amplifying horn or a distortion of such tones or other sounds, I desirably make the entire 55 amplifying horn as well as the adjacent ends of the two inlets leading thereto of a square section, substantially as shown in Fig. 60 3. Then by using a rectangular flap, I can cause this flap to be disposed in substantial 65 continuation of the outer surface of one of the inlet bends when in either of its two operative positions. In other words, I am able to maintain tonal passages which will

gradually increase in cross-section towards the mouth of the horn with substantial uniformity from each of the inlets, and my construction permits me to do this without introducing complications of any kind and without affording side passages which might tend to muffle or distort the tones or other sounds. 70

However, while I have illustrated and described my invention in an embodiment including desirable details, I do not wish to be limited to the construction and arrangement thus disclosed, it being obvious that the same might be modified in many ways without departing from the spirit of my invention. 75 80

I claim as my invention:

1. A sound reproducing apparatus comprising a wireless receiving set, a phonograph, an amplifying horn having a pair of inlets respectively associated with the phonograph and with the wireless receiving set, means including a movable valve for normally shutting off the inlet connection to the phonograph, and automatic means for moving the valve to cause the same to shut off the inlet connection associated with the wireless receiving set when the phonograph is in operation. 85 90

2. A sound reproducing apparatus comprising a wireless receiving set, a phonograph, an amplifying horn having a pair of inlets respectively associated with the phonograph and with the wireless receiving set, movable means normally actuated by gravity 100 for shutting off the inlet connection to the phonograph, while leaving the wireless receiving set connected to the horn through the other inlet, and automatic means for annulling the said shut-off of the phonograph and shutting off the inlet connection to the wireless receiving set when the phonograph is in use. 105

3. A sound reproducing apparatus comprising a wireless receiving set, a phonograph, an amplifying horn having a pair of inlets respectively associated with the phonograph and with the wireless receiving set, a control member arranged for shutting off either one or the other of the inlets, means 110 for normally holding the control member in a position in which it shuts off the inlet from the phonograph, and control means responsive to the operation of the phonograph for moving the control member to the position in 115 which it shuts off the inlet connection to the wireless receiving set and establishes the inlet connection to the phonograph. 120

4. A sound reproducing apparatus comprising a wireless receiving set, a phonograph, an amplifying horn having a pair of inlets respectively associated with the phonograph and with the wireless receiving set, a control member arranged for shutting off either one or the other of the inlets, an elec- 125 130

- tric motor for driving the phonograph, movable means arranged for normally holding the control member in a position in which it shuts off the inlet connection from the phonograph, and control means responsive to the supply of current to the motor for moving the control member to a position in which it shuts off the inlet connection to the wireless receiving set.
- 5 5. Sound reproducing apparatus as per claim 1, including a rock shaft, the control member being fast upon said rock shaft; the control means including a solenoid having its winding in series with the motor, and connections whereby the solenoid rocks the shaft.
- 10 Signed at Chicago, Illinois, February 24th, 1922.
